CLAIM

The ornamental design for a sawing table, as shown and described.

DESCRIPTION

FIG. 1 is a front perspective view of the sawing table of the present invention;

FIG. 2 is a second front perspective view of the invention of FIG. 1;

FIG. 3 is a front elevational view of the invention of FIG. 1;

FIG. 4 is a rear elevational view of the invention of FIG. 1;

FIG. 5 is a right side elevational view of the invention of FIG. 1;

FIG. 6 is a left side elevational view of the invention of FIG. 1;

FIG. 7 is a top view of the invention of FIG. 1; and,

FIG. 8 is a bottom view of the invention of FIG. 1.

1 Claim, 5 Drawing Sheets
